**COMBINED LIFT PLUG, PICK-UP SUB AND
THREAD PROTECTOR FOR ROTARY DRILL
COLLARS**

James Kirk Salter, 1301 W. Park Ave., Eunice, La.

Filed July 25, 1961, Ser. No. 66,066

Term of patent 14 years

(Cl. D54—4)

FIGURE 1 is a side elevational view of a combined lift plug, pick-up sub and thread protector for rotary drill collars.

FIGURE 2 is a top plan view.

FIGURE 3 is a bottom plan view thereof.

I claim:

The ornamental design for a combined lift plug, pick-up sub and thread protector for rotary drill collars, substantially as shown.
